SCORE-CUT SLITTING MECHANISM

Elvin A. Mastriani, Caldwell, N. J., assignor to John Dusenberry Co., Inc., Verona, N. J., a corporation of New Jersey

Application November 9, 1953, Serial No. 390,852

3 Claims. (Cl. 164—60)

This invention relates to score-cut slitting apparatus for use in connection with machines for slitting flexible sheet material such as paper, plastic, etc. and commonly referred to as pellicles.

In machines of the class to which this invention relates, a rotatable cutting knife is pressed against the web of flexible material as the latter passes over a steel platen or backing roll. Such cutting arrangements are known as contact slitters and the two problems associated therewith are the application of a controlled pressure to the cutting knives, and the construction of the cutting knives so as to permit slitting a sheet of material into a plurality of ribbons having relatively narrow widths of the order of $\frac{1}{2}$ inch or less. The pressure of the cutting knife preferably is controlled by providing fluid-actuated arrangements for pressing the knife against the backing roll and while various such arrangements have heretofore been proposed they involve complex and costly constructions that include mechanical levers and/or linkages. Such prior constructions are subject to wear and, in general, require a specific orientation of the cutting knife relative to the backing roll. Relatively narrow cutting wheel arrangements have also been proposed but these have been of the individual spring-biased type and difficulty is encountered in maintaining the individual spring tensions so as to produce a uniform pressure of a plurality of cutting wheels against the backing roll particularly in high speed cutting machines subject to vibration during operation.

In general, it is preferable to have the cutting knives operated by air pressure of the order of 60 pounds per square inch such air pressure system being used for sundry other purposes in paper-cutting establishments. However, so far as I am aware the problem of providing relatively narrow cutting wheels actuated by such air-pressure systems has not been solved heretofore.

Exemplary of the prior art constructions are those disclosed in United States Patent No. 2,043,818 issued on June 9, 1936, to A. J. Thibedeau, United States Patent No. 2,541,913 issued on February 13, 1951, to T. N. Carter and United States Patent No. 1,895,852 issued on January 31, 1933, to R. Johnstone.

An object of this invention is the provision of a cutting knife for a score-cut slitting machine, which knife is of simple, rugged, economical construction and which is of a minimum overall thickness whereby a plurality of such knives can be arranged in side-by-side disposition to cut a sheet of material into a plurality of ribbons of relatively narrow width, say, or the order of $\frac{1}{2}$ inch or less.

An object of this invention is the provision of a rotary cutting knife for slitting machines which knife includes a housing adapted for fixed attachment to the machine and a cutting wheel movable outwardly of the housing in response to fluid pressure.

An object of this invention is the provision of a score-cut slitting mechanism comprising a housing, a slide member slidable in alined slots in the housing and carrying

2

a rotatable cutting wheel, a piston operable in a cylinder and connected to the slide member by a laterally-flexible rod, and means for connecting the cylinder to a source of fluid pressure whereby the cutting wheel can be forced against a backing roll with a predetermined pressure.

An object of this invention is the provision of fluid-pressure-operated cutting wheels for a paper-slitting machine, said wheels being mechanically-biased to an inoperative position away from a backing roll upon a reduction in the fluid pressure thereby facilitating the threading of the paper over the backing roll and without endangering the operator.

These and other objects and advantages will become apparent from the following description when taken with the accompanying drawings. It is to be understood the drawings are for purposes of illustration and are not to be construed as defining the scope or limits of the invention, reference being had for the latter purpose to the appended claims.

20 In the drawings wherein like reference characters denote like parts in the several views:

Figure 1 is a side view illustrating my fluid-pressure-operated cutting wheel advanced to the operative position relative to a backing roll;

25 Figure 2 is a central, longitudinal, sectional view of the device shown in Figure 1 and showing the cutting wheel in the retracted position;

Figure 3 is a transverse sectional view taken along the line 3—3 of Figure 2 and drawn to an enlarged scale;

30 Figure 4 is a front view showing a plurality of slitting mechanisms arranged in side-by-side relation on a paper slitting machine;

Figure 5 is a sectional view taken along the line 5—5 of Figure 4;

35 Figure 6 is similar to Figure 4 and showing a modified arrangement of the cylinders and connecting hose;

Figure 7 is an enlarged elevation view of the longitudinally-rigid and laterally-flexible control rod that connects the piston of the air-cylinder to the slide bar carrying;

40 Figure 8 shows several cutting wheels in side-by-side abutting relation and is presented to illustrate the self-supporting yet laterally-displaceable character of the connections between the air cylinders and the slitter housing.

45 Referring now to Figures 1—3, each cutting mechanism comprises cutting wheel 1 pivotally carried by a bifurcated slide bar 3 that is adapted for linear movement within the alined slots 4 formed in the parallel, spaced, metal plates 2 and 2'. These plates are separated by a plurality of metal spacers 24, 25, 26, the parts being rigidly secured together by means of suitable, socket screws 5.

Threaded into an end of the slide bar 3 is a laterally-flexible control rod 7 that passes through a threaded connector 8 secured to an end of the hose 9, which hose may be either flexible or rigid to meet specific requirements. The control rod, which will be described in detail with reference to Figure 7, terminates within a closed cylinder 10 and has attached thereto a piston 11 and a leather, cup-like washer 12, or other suitable means to form a fluid tight seal between the piston and the cylinder. Fluid is admitted into the top of the cylinder through a flexible hose 13 provided with a conventional quick-connect coupling C. It will be apparent that fluid under pressure will force the piston downwardly overcoming the biasing force of the coiled spring 15. Such movement of the piston results in a corresponding movement of the control rod 7, the slide bar 3 and the cutting wheel 1, the latter being pivotally secured to the slide bar by means of a ball bearing 21 and the screw 22.

55 It is pointed out that the slide bar assures a true linear movement of the cutting wheel and that the limit of travel of the wheel, in one direction or the other, is

60

defined by the end walls forming the alined slots 4 in the spaced plates 2, 2'. In order to illustrate this movement of the cutting wheel, Figure 1 shows the cutting wheel in its advanced, or operating position, in contact with the backing roll 23, it being noted that the lower end of the slide bar is spaced from the lower end of the slots. In Figure 2, the cutting wheel is shown in the retracted, or inoperative, position with the upper end of the slide bar in contact with the walls defining the upper ends of the slots. Those skilled in this art will understand that the pellicle, such as a paper sheet or other flexible sheet material, to be cut passes over the hardened steel backing roll and is slit by the cutting wheel. The optimum pressure of the cutting wheel against the backing roll depends upon the thickness, toughness and the speed of travel of the pellicle and the required contact pressure can be obtained by varying the pressure of the fluid in the cylinder.

To facilitate mounting the slitter on a machine the lower portions of the plates 2, 2' are provided with integral, undercut ends 27. Spaced from these ends is a triangular member 20 pivotally secured between the plates 2, 2' as by a dowel pin. A hardened socket screw 28 operates in a threaded hole in the end plate 16, the latter being secured to the spacer members 25, 26 by socket screws 30. By turning the socket screw 28 so that it advances downwardly the triangular member 20 will be forced in a counter-clockwise direction to lock the entire device on a dovetailed support bar 31 that is attached rigidly to the paper slitting machine.

Attention is directed to the fact that my slitting wheel mechanism is of simple, rugged construction employing a direct transmission of linear motion between the piston of the air cylinder and the cutting wheel. The elimination of levers and/or pivot points promotes long, trouble free operation particularly in high speed paper slitting machines wherein the cutting wheel is forced against the backing roll by a relatively high pressure. Equally important is the fact that a slitting mechanism made in accordance with my invention can be made relatively thin (permitting a side-by-side mounting of a plurality of cutting wheels to slit a flexible sheet into relatively narrow ribbons, say, $\frac{1}{2}$ inch or less) and the individual cutting wheels can be actuated by air pressure through air cylinders located remote from the housing of the slitting wheels.

Figures 4-6 illustrate two types of installations of my narrow cutting mechanisms on a paper slitting machine. In Figure 4, the backing roll 23 is shown journaled between side frames, said frames also carrying the dovetailed support bar 31 and a cross bar 33 to which the cylinders 10 are attached. As shown clearly in Figure 5, which is a sectional view taken along the line 5-5 of Figure 4, the cylinders are shown closely positioned in two horizontal rows. The front row of cylinders operate the cutting wheels 2, 4, 6 and 8, taken from the left, whereas the rear row of cylinders operate the cutting wheels 1, 3, 5 and 7. Each of the cylinders is connected to a header 34, by the flexible hoses 13, which header is connected to a suitable source of fluid pressure, as by a hose 35, and serves as a distribution means for feeding such fluid under pressure to the various cylinders connected thereto. Those of the header openings to which cylinders are not connected are, of course, closed with a suitable cap. In practice, I employ cylinders having an outside diameter of approximately 1 inch and make the thickness of the cutting wheel mechanism somewhat less than $\frac{1}{2}$ inch. Consequently, with the cylinders arranged as shown in Figures 4 and 5 the cutting wheel mechanisms can be set side-by-side along the support bar 31 to slit the paper sheet into a plurality of ribbons having a width somewhat less than $\frac{1}{2}$ inch.

While in the Figures 4, 5 arrangement all of the flexible connecting hoses are of equal lengths thereby promoting manufacturing economy, a staggered arrangement

may be preferred. Such staggered arrangement is shown in Figure 6 wherein the cylinders are positioned in two vertical rows. The flexible hoses 9', connected to the cutting wheels 2, 4, 6 and 8, are relatively long whereby the associated cylinders may be secured to the upper cross bar 33 whereas the hoses 9, connected to the cutting wheels 1, 3, 5 and 7, are relatively short and the associated cylinders are secured to the lower cross bar 33'. Although I show ample clearance between the flexible hoses of the upper cylinders and the lower cylinders it will be apparent that the housings of the cutting wheel mechanisms can be positioned against each other thereby reducing the width of the cuts.

Figure 7 illustrates the control rod which connects the piston of the air cylinder to the slide bar carrying the rotatable cutting wheel. The control rod comprises the metallic rod sections 7a, 7b joined to a bundle of steel wires 7c as by soldering, welding, etc. The lower rod section 7a is provided with a threaded end adapted for threaded attachment to the slide bar whereas the upper rod section 7b is similarly threaded to accept a cooperating nut for fastening the piston thereto. A coiled spring 7d encircles the wires 7c and has its ends securely attached to the rod sections 7a, 7b, as shown. It will be apparent that such construction results in an arrangement which is self-supporting, will transmit forces axially of the rod but is laterally-flexible to a certain extent. This permits the air cylinder to operate the slide bar even though the cylinder axis is not in direct alinement with the plane of movement of the slide bar and the cutting wheel.

In more or less permanent installations of the cutting wheels on a paper slitting machine, such as those shown in Figures 4-6, the laterally-flexible character of the control rod, when the latter is enclosed within a flexible hose, permits the off-center positioning of the air cylinders for attachment to the cross bars of the machine. Also, the positional arrangement of the air cylinders can be achieved with rigid hose or pipe by prebending such pipe as required. However, in a majority of cases it is preferable that the installation of the cutting wheels offer a maximum of flexibility to permit the ready addition or removal of cutting wheels to meet varying requirements. It is in such arrangement that the construction of my cutting mechanisms affords decided advantages over prior devices of this type. Since the control rod is of a self-supporting character there is no necessity to secure the air cylinders to supporting members carried by the machine. Figure 8 shows several cutting wheel mechanisms mounted in side-by-side abutting relation on the dovetailed bar 31 to provide the narrowest cuts. The air cylinders 10 are supported by the control rod and hose 9. Since the rod and hose are laterally-bendable the air cylinders can be of a diameter exceeding the width of the cutting mechanism housings. The cylinders will be bunched together with some or all out of direct alinement with their associated slide bars but this in no way affects the linear movement of the cutting wheels in response to air or liquid pressure applied to the associated pistons. The enlarged-diameter air cylinders make it possible to employ air under safe pressure as the driving force and yet apply the necessary pressure of the cutting wheel against the backing roll.

Having now described my invention, certain changes and modifications in the construction and assembly of the various parts will occur to those skilled in this art. Although I prefer to use a flexible hose between the fluid cylinder and the cutting wheel housing such hose may be rigid and pre-bent to desired shape to meet specified design requirements. Further, in the event fluid-operated mechanisms are not required a coiled spring, such as the spring 15 shown in Figure 2 can be positioned on the other side of the piston to force the cutting wheel against the backing roll. In the latter case the pres-

sure of the cutting wheel against the backing roll can be varied by providing a threaded end cap on the cylinder whereby screwing the end cap in one direction or the other will compress the spring more or less between the end cap and the piston. These and other variations and modifications can be made without departing from the spirit and scope of the invention as set forth in the following claims.

I claim:

1. The combination with a cylindrical rotary backing member; of a score-cut slitting unit associated therewith including an elongated slide bar having a bifurcated end and being mounted for sliding movement along its longitudinal axis, a cutting wheel rotatably carried by and between the bifurcations of said slide bar for movement therewith in both directions, means guiding the slide bar for radial movement with respect to said backing member, a cylinder one end of which is adapted to receive fluid under pressure, a piston slidably housed within the said cylinder, a laterally flexible rod having one end connected to the piston, said rod passing outwardly from the other end of the cylinder and having its other end connected to the slide bar, and spring means biasing the piston toward the first-mentioned end of the cylinder.

2. The invention as recited in claim 1, wherein the cylinder is flexibly mounted on said guiding means for movement laterally of the axis thereof, and wherein the laterally flexible rod comprises axially spaced rigid rod sections, a plurality of wires having ends secured to ad-

jacent ends of said rod sections, and a helical spring encircling said wires and having its ends secured to said rod sections.

3. The invention as recited in claim 1, including a plurality of said units closely spaced to thereby form narrow widths of slit material, and in which the laterally flexible rod of each allows the cylinders to be of a diameter exceeding the spacing distance and offset from the lines of movement of said slide bars.
